UNITED STATES PATENT OFFICE.

ROBERT H. WENTORF, OF WEST BEND, WISCONSIN, ASSIGNOR TO WEST BEND ALUMINUM COMPANY, A CORPORATION OF WISCONSIN.

COOKER VALVE.

Application filed March 2, 1922. Serial No. 540,468.

The invention relates to escape valves and is more particularly directed to that class of valves used for cooking vessels such as boilers or steamers, and has for its primary 5 object the provision of a valve that may be so assembled as to provide either an automatically operated valve or a valve that can be manually operated to secure the valve closure member in either open or closed position.

A further object of the invention is to provide a valve, simple in construction, having few parts and economical of manufacture.

The invention is more particularly applicable to that class of steamers or boilers having a cover with what is known as a steam tight fit.

Other objects of the invention will appear from the following description, which is directed to the preferred embodiment of the invention, reference being made to the accompanying drawings forming a part of the specification, in which:

Fig. 1 is a top plan view of a cover for a 25 boiler with my invention attached thereto, a part of the cover being broken away.

Fig. 2 is a vertical sectional view of Fig. 1 taken on line 2—2.

Fig. 3 is a central fragmentary section of 30 the cover with the valve removed.

Fig. 4 is a fragmentary vertical section of the cover taken on line 4—4 of Fig. 3.

Fig. 5 is a detail elevational view of the operating plate for the valve shown in full 35 lines with the spacing plate shown in dotted lines and in one position with relation to the operating plate.

Fig. 6 is a detail elevational view of the spacing plate.

Fig. 7 is a detail elevational view of the 40 assembled valve with the spacing plate in closer relation to the operating plate.

Referring now to the drawing for a more 45 particular description of my invention, the reference character 10 represents a cover for a boiler having downwardly struck spherical concavity 11 in the approximate center thereof, which has aperture 12 therethrough and concentric with the concavity 11 through which aperture valve stem 13 is adapted to have reciprocal movement, there being a clearance between the periphery of the aperture 12 and the valve stem 13 for the escape of steam from the boiler when 55 the valve is in open position. Valve stem 13

carries at its upper extremity an operating plate 14, which has upstanding ears 15 forming convenient means for rotating the plate with the fingers. Operating plate 14 has spacing studs 16 depending from the bottom 60 thereof. Valve stem 13 is enlarged at its upper portion and adjacent operating plate 14 into a substantially spherical shaped closure member 17, which is adapted to seat in the concavity 11 and close aperture 12. Spacing plate 18 carries on its upper face spacing studs 19 and is non-rotatably mounted on the lower portion of valve stem 13 with the upper extremities of spacing studs 19 lying in the same vertical plane as spacing studs 16 of the operating plate and spaced therefrom, as clearly shown in 70 Figs. 5 and 7. Cover 10 is provided with a plurality of shoulders or bosses 20, which are preferably upstruck from the 75 material forming the cover and being so spaced with relation to the aperture 12 as to be in the line of movement of spacing studs 16 and 19 when the operating plate 14 is rotated. Cover 10 is also provided with 80 handles 21, which handles lie in a plane above the top of the upstanding ears 15 of the operating plate 14, thereby serving the double purpose of providing lifting handles for the cover and protecting means for the 85 valve seat when the cover is laid or tossed upon a table, the handles 21 preventing the operating plate from coming in contact with the table when the cover is laid bottom up thereon.

It will readily be seen by reference to Figs. 3, 4 and 7 that if operating plate 14 be so positioned that the spacing studs 16 rest on the tops of the shoulders or bosses 20 the spacing studs 19 carried by the spacing plate 90 18 will contact with the upper wall of recesses 22 which are formed on the under side of the cover by the formation of shoulders or bosses 20.

Referring to Fig. 7, it will be readily seen 100 from the foregoing that if the spacing studs 16 and 19 be so placed with relation to each other as to leave a space therebetween equal to the thickness of the material forming the cover 10, and the studs 16 are placed upon the tops of the shoulders or bosses 20 the valve will be secured in open position, whereas, if the operating plate 14 be so positioned as to place the spacing studs 16 intermediate the shoulders or bosses 20 the 105 110

spacing studs 19 will engage the inner face of cover 10, thereby securing the valve in closed position.

In Fig. 5 I have shown the spacing member 18 in dotted lines as carried by the valve stem 13 with the extremities of spacing studs 19 at a greater distance from the extremity of the spacing stud 16 than the thickness of the material forming the cover 10.

With the valve members assembled as just described the valve will become automatic and will be forced into open position by the contact of the steam with the closure member 17 and so held until the pressure of the steam within the boiler is lowered sufficiently for the closure member 17 to reseat by reason of the weight of spacing plate 18. It will be readily seen however that should the operating plate 14 be rotated in such manner as to cause the spacing studs 16 to rest upon the tops of shoulders or bosses 20 the valve will be secured in open position.

From the foregoing disclosure it will be seen that I have provided a valve structure which may be used as a simple gravity actuated poppet valve or a valve that may be locked in open position or a valve that may be locked in either opened or closed position without the alteration of any of its parts.

Having thus described my invention, what I claim is:

1. The combination with a cover for a boiler having a spherical concavity therein, an aperture through the concavity and bosses on the outer side of the cover, of an operating plate, a closure member carried by the operating plate, said closure member having a stem adapted to have reciprocal movement in the aperture, a spacing plate affixed to the lower portion of the stem, upstanding spacing members carried by the spacing plate, and dependent spacing members carried by the operating plate.

2. The combination with a cover for a boiler having a spherical concavity therein, an aperture through the concavity and bosses on the outer side of the cover, of an operating plate, a closure member carried by the operating plate, said closure member having a stem adapted to have reciprocal movement in the aperture, a spacing plate affixed to

the lower portion of the stem, upstanding spacing members carried by the spacing plate, and dependent spacing members carried by the operating plate and in vertical alignment with the spacing members of the spacing plate.

3. The combination with the cover of a boiler provided with a spherical concavity having an aperture formed therein, of a closure member co-operable with said concavity and having a stem adapted for reciprocal movement in said aperture, an operating plate associated with said member and stem, bosses formed on said cover, means associated with said plate and co-operable with said bosses for controlling the position of said member, and means associated with said stem for limiting the movement of said member.

4. The combination with a cover for a boiler having a spherical concavity therein, an aperture through and concentric with the concavity, upstruck portions of the cover forming bosses on one face thereof, and recesses on the opposite face thereof, of a closure member, a stem carried by the closure member and adapted to have movement in the aperture, an operating plate affixed to the closure member, dependent spacing members secured to the operating plate, a spacing plate secured to the lower portion of the stem, upstanding spacing members secured to the spacing plate, and means for rotating the operating plate, the said bosses lying in the path of rotation of the spacing members carried by the operating plate.

5. The combination with a cover for a cooking vessel having an apertured valve seat therein, of a boss formed in the cover at one side with a co-related depression at the other, and a closure member adapted to engage the said seat and having a stem passing through the aperture and carrying projections at opposite sides of the cover, one of said projections being adapted to ride over the boss and the other to enter the depression when the valve member is rotated.

In testimony whereof I have signed my name to this specification on this 24th day of February A. D. 1922.

ROBERT H. WENTORF.
